UNITED STATES PATENT OFFICE.

WILLIAM E. HARLOE, OF HIGH VIEW, WEST VIRGINIA.

GAUNTLET.

SPECIFICATION forming part of Letters Patent No. 588,426, dated August 17, 1897.

Application filed February 1, 1897. Serial No. 621,386. (No model.)

To all whom it may concern:

Be it known that I, WILLIAM E. HARLOE, a citizen of the United States, residing at High View, in the county of Hampshire and State of West Virginia, have invented certain new and useful Improvements in Gauntlets and Gloves; and I do hereby declare the following to be a full, clear, and exact description of the invention, such as will enable others skilled in the art to which it appertains to make and use the same.

This invention relates to improvements in gloves, and has more particular relation to gauntlets.

15 The invention consists of certain novel constructions, which will be hereinafter more particularly set forth and claimed.

In the accompanying drawings, forming part of this specification, Figure 1 represents 20 a perspective view of my improved gauntlet, and Fig. 2 represents an enlarged detail perspective view of the hinged strips and annular contracting-ring.

1 in the drawings represents the glove 25 proper, 2 the cuff of the same, and 3 the contracting-spring. The glove 1 may be of any desired construction, and the sleeve or cuff 2 is applied to the same as in the ordinary construction of gauntlets. The said cuff 2 30 may be made continuous, but is preferably slit longitudinally along the back, as at 4, to permit of its being expanded beyond its normal diameter for the insertion of the coat-sleeve therein. The edges of this slit portion 35 4 are preferably bound with metal strips 5, as shown in the drawings, so that the cuff may be readily opened by grasping said strips and pulling them apart. These strips are hinged together at their forward ends, so as 40 to prevent any possibility of their cutting the material of which the glove or cuff is formed. The spring 3 is constructed of flat band-steel in such manner that it normally lies with its two free ends overlapping. This spring is 45 applied in the rear edge of the cuff 2, in a suitable casing 6, formed for its reception, and thus normally contracts the cuff to less than its real diameter by causing the edges of the split portion to overlap. The respective 50 ends of the spring 3 are riveted or otherwise connected to the free ends of the strips

5. By this construction both the inner edge of the gauntlet as well as the edges of the split portion are held firmly in position without any liability of the cuff being rumpled 55 or pushed forward of the sleeve and thus permit the entrance of air.

In the use of gauntlet-gloves by persons exposed to severe temperatures it has been found that when the cuffs are made sufficiently large to permit the coat-sleeves to be slipped within the same they flare at their rear ends, and thus permit the entrance of cold air into the interior of the glove and up the sleeve of the wearer. In order to altogether obviate this defect, I have provided my improved construction of gauntlet, which when applied in position on the wearer's hand and arm tightly contracts upon and hugs the coat-sleeve and thus effectively prevents the 65 entrance of any cold air. This gauntlet is particularly useful to trainmen and others exposed to very severe weather for prolonged periods. The adjustment of the split cuff to the coat-sleeve of the wearer is altogether automatic and requires no attention upon the 70 part of the wearer after the glove is once adjusted.

Having thus described my invention, what I claim as new, and desire to secure by Letters 80 Patent, is—

The combination with a gauntlet-glove having a cuff formed with a placket, of independent stiffening-strips applied along the edges of said placket and hinged together at their forward ends, and a contracting-spring secured about the rear edge of said cuff and having its respective ends secured to the free ends of the strips which extend along the placket edges so that the cuff will be held rigidly against any longitudinal pressure but at the same time be contracted firmly about the sleeve of the wearer, substantially as described.

In testimony whereof I have signed this 95 specification in the presence of two subscribing witnesses.

WILLIAM E. HARLOE.
